UNITED STATES PATENT OFFICE.

WILLIAM H. GAILOR, OF SARATOGA SPRINGS, NEW YORK.

ROAD-OILER.

962,209.

Specification of Letters Patent. Patented June 21, 1910.

Application filed July 24, 1909. Serial No. 509,458.

To all whom it may concern:

Be it known that I, WILLIAM H. GAILOR, a citizen of the United States, residing at Saratoga Springs, in the county of Saratoga and State of New York, have invented an Improvement in Road-Oilers, of which the following is a specification.

My present invention relates to an apparatus for supplying oil or other material to the surface of a road and particularly a dirt or macadam road in contradistinction to a road having a block pavement of either wood or stone, and the object thereof is the laying of the dust and preventing an accumulation or making of appreciable mud in wet weather.

My invention is also an improvement on the road oiler apparatus shown and described in my copending application Serial No. 472419, filed January 15th, 1909, and duly allowed May 8th, 1909, in which apparatus the delivery of the oil or the mixture of the same with a predetermined quantity of steam was effected through a series of apertures provided in the lower portion of a delivery pipe employed for this purpose, whereas in the present case the invention relates particularly to the oil delivery member which is so constructed as to deliver the oil or a mixture of the same with steam in a thin sheet, this oil delivery member being provided with means whereby the width of the slot through which the oil is ejected may be varied at the pleasure of the operator, to determine the thickness of the sheet of oil delivered.

In carrying out my invention, I employ a tank and an auxiliary receptacle, together with a reservoir from which the oil is adapted to be delivered in sheet form upon the surface to be treated, means for connecting the tank to the auxiliary receptacle and means for conveying the oil from the auxiliary receptacle to the delivery reservoir and for regulating the distribution of the same in the latter, means for heating the oil in the auxiliary receptacle and also for conveying the heat from the auxiliary receptacle to the delivery receptacle and for heating the oil in the latter, and means for varying the size of the opening in the delivery receptacle through which the oil is ejected therefrom, all of which will be hereinafter more particularly described.

In the drawing, Figure 1 is an elevation and partial section of an apparatus embody-

ing my present invention. Fig. 2 is an enlarged end elevation of the oil delivery reservoir. Fig. 3 is a cross section on line x , x ; Fig. 1, and Fig. 4 is a partial cross section illustrating a modified structure for adjusting the size of the oil delivery slot.

Referring particularly to the drawing, 10 designates a tank or receptacle adapted to receive the oil to be employed and in which the same is stored.

11 designates an auxiliary pipe or receptacle and 12 a pipe connecting the tank 10 and the auxiliary receptacle 11, and 13 a valve which is placed in the pipe 12.

14 designates a delivery reservoir and 15 represents a series of pipes, any convenient number of which may be employed and each one of which extends between and connects the auxiliary receptacle 11 with the delivery reservoir 14, and furthermore each of the pipes 15 is provided with a valve 16 by means of which, as will be apparent, the amount of oil flowing from the auxiliary receptacle 11 to the delivery reservoir 14 may be determined and also its distribution may be regulated.

Except for the construction of the delivery reservoir, the parts hereinbefore described, are similar to those shown and described in my application aforesaid, and as is also shown and described in said application, I prefer to employ a steam pipe 17 extending entirely throughout the length of the auxiliary receptacle 11 and being contained therein and a steam pipe 18 passing through one end of the delivery reservoir 14 and extending throughout the length of the same and being connected to the steam pipe 17 by a pipe 19 or otherwise, and the steam pipe 18 within the delivery reservoir 14 is provided with a series of apertures 20 through which the steam is ejected and permitted to commingle with the oil, the mixture of which is delivered from the reservoir 14 to accomplish the purpose of this apparatus.

Now the particular feature to which the present invention relates as herein stated, comprises the delivery reservoir 14 and in constructing the same, I prefer to employ a channel iron 21 which is employed in an inverted position and forms the top member of this delivery reservoir, the sides of which are preferably made of sheet metal indicated respectively at 22, 23. These side members are secured to the depending por-

tions of the channel iron by means of bolts 24 or otherwise, and the side members 22, 23 converge from the edges of the said depending portions of the channel iron to a 5 point adjacent to their lower edges at which an elongated opening is provided between them preferably in such a manner as to be parallel sided and through which the oil or a mixture of the same with steam is ejected, 10 this delivery opening being indicated at 25.

At the extremities of the delivery reservoir there are end members 26, 27, which are secured in position to the channel iron 21 by means of bolts 28 or otherwise.

15 29 designates a bar which extends between the end members 26, 27, and is secured thereto and also to the lower edge of the side member or apron 22, and 30 designates a bar which extends between the end members 26, 27, and is not secured thereto but is secured to the lower portion of the side member or apron 23.

As will be seen by particular reference to Figs. 2 and 3, the end members 26, 27, are provided with projecting portions indicated at 35 and extending between these projecting portions 35 and secured thereto, is a bar indicated at 31. Passing through and engaging the bar 31 I employ a plurality of 30 adjusting bolts 32 and at its inner end each of these adjusting bolts is provided with an annular recess 33. This recessed portion of each bolt 32 is passed into an aperture provided therefor in the bar 30 and in alinement with the bolt hole in the bar 31 and for each adjusting bolt 32, the bar 30 in its lower portion is provided with a screw 34 provided with a reduced end or pin 36 which latter extends into the annular recess 33 provided in the bolt, and as will be apparent, the turning of the respective bolts 32 will cause a movement of the bar 30 and a corresponding movement of the lower portion of the movable side member or apron 23 and 45 will effect a corresponding adjustment of the sides of the slot 25 through which the oil or a mixture of the same and steam is delivered.

It will be understood that I do not limit myself to the hereinbefore described means 50 for adjusting the size of this slot, as manifestly there are numerous other constructions for accomplishing this purpose. For instance, as is shown in Fig. 4, the end of each adjusting bolt may be reduced as indicated at 37, this reduced portion of the bolt being passed through an aperture provided therefor in the bar 30 with the shoulder formed by the reduced portion abutting against the outer face of the bar 30. In this 55 instance the inner face of the bar 30 is provided with a series of recesses 38, each of which is concentric with an aperture provided for the reduced end of an adjusting bolt and is adapted to receive a washer 39

which is secured therein by turning the end 6 of the reduced portion 37 down against the washer or otherwise, this washer as will be apparent, being placed between the adjacent surface of the lower portion of the apron 23 and the bar 30 and lying wholly within the 70 recess 38 provided therefor in the bar 30. In this instance as will also be understood, the size of the delivery slot is decreased by the shoulders on the bolts 32 forcing the bar 30 from right to left as shown in Fig. 4, 75 and the size of the slot increased by the washers 39 or other member bearing against the faces of the recesses 38 and moving the bar 30 in the other direction when the bolts are turned the other way.

I claim as my invention:

1. In a road oiling device, a delivery reservoir, comprising a cover, end members, side members having converging upper parts and straight parallel lower parts, the latter terminating in spaced apart parallel edge portions and means for varying the distance between the said spaced apart parallel edge portions of the said side members.

2. In a road oiling device, a delivery reservoir comprising a top member, end members, a fixed side member, a movable side member, said side members converging downwardly and terminating in parallel sided edge portions which are spaced apart 95 to provide a delivery slot, and means for adjusting the position of the said movable side member relatively to that of the said fixed side member to vary the size of the slot between the said parallel sided edge portions 100 thereof.

3. In a road oiling device, a delivery reservoir comprising a top member, end members, a fixed side member, a movable side member, the said side members converging 105 downwardly to parallel sided edge portions which are spaced apart to provide a delivery slot, a bar fixed in the said end members, a bar secured to the lower portion of the said movable side member, adjusting bolts operating in the said bar which is fixed in the said end members and passing through the said bar secured to the said movable side member and means engaging the ends of the said adjusting bolts within the last afore- 110 said bar, whereby the same is moved by turning the said adjusting bolts to vary the position of the said movable side member relatively to that of the said fixed side member to determine the width of the slot between the said parallel sided portions of the 115 said side members.

Signed by me this 21st day of July, 1909.

WILLIAM H. GAILOR.
